US0D1004849S

(12) **United States Design Patent** (10) **Patent No.:** **US D1,004,849 S**
(45) **Date of Patent:** **** Nov. 14, 2023**

(54) **COMPACT ATOMIZER**

(71) Applicant: **Loop Laboratories, LLC**, Chicago, IL (US)

(72) Inventor: **Scott H. Wilson**, Chicago, IL (US)

(73) Assignee: **Loop Laboratories, LLC**, Chicago, IL (US)

(**) Term: **15 Years**

(21) Appl. No.: **29/788,487**

(22) Filed: **Jun. 8, 2021**

(51) LOC (14) Cl. **28-03**

(52) U.S. Cl.

USPC **D28/91.1**

(58) **Field of Classification Search**

(57) **CLAIM**

The ornamental design for a compact atomizer, as shown and described.

DESCRIPTION

FIG. 1 is a front view of a compact atomizer.

FIG. 2 is a rear view of the compact atomizer shown in FIG. 1, opposite of the front view shown in FIG. 1.

FIG. 3 is a side view of the compact atomizer shown in FIG. 1.

FIG. 4 is a side view of the compact atomizer shown in FIG. 1, opposite of the side shown in FIG. 2.

FIG. 5 is a top view of the compact atomizer shown in FIG. 1.

FIG. 6 is a bottom view of the compact atomizer shown in FIG. 1, opposite the top view shown in FIG. 4; and,

FIG. 7 is a perspective view of the compact atomizer shown in FIG. 1.

The broken lines depict portions of the inhalant dispenser that form no part of the claimed design.

1 Claim, 6 Drawing Sheets
